UNITED STATES PATENT OFFICE.

LEVI S. GARDNER, OF NEW ORLEANS, LOUISIANA.

EXPLOSIVE-ENGINE.

1,072,596.

Specification of Letters Patent.

Patented Sept. 9, 1913.

Application filed June 19, 1906, Serial No. 322,379. Renewed January 5, 1912. Serial No. 669,722.

To all whom it may concern:

Be it known that I, LEVI S. GARDNER, a citizen of the United States, residing at New Orleans, parish of Orleans, State of Louisiana, have invented a certain new and useful Improvement in Explosive-Engines, and declare the following to be a full, clear, and exact description of the same, such as will enable others skilled in the art to which it pertains to make and use the same, reference being had to the accompanying drawings, which form a part of this specification.

My invention has for its object the production of an explosive engine, possessing the following advantages, to wit: 1. An engine in which the explosive mixture after the explosion is expanded to atmospheric pressure, thus utilizing the full efficiency of the explosion in power. 2. By thus expanding the explosive mixture to atmospheric pressure and thus exhausting it into the air the exhaust is silent and the necessity of a muffler obviated. 3. An engine in which, because of the expansion of the explosive mixture to atmospheric pressure, the cylinder will not run as hot as in the ordinary structure and can be easily air-cooled without the necessity of a water jacket.

In the drawings Figure 1 is a horizontal section with parts in elevation of my improved engine; Fig. 2 is a section on the line 2—2 Fig. 1; Fig. 3 is a section in detail of the cam for operating the exhaust valve; Fig. 4 is a vertical section with parts in elevation of a variation in the structure; Fig. 5 is a detail of the top of what might be termed the gas or valve ring; Fig. 6 is a view of the under-side of the same; Fig. 7 is an enlarged cross section on the line 7—7 of Fig. 4; Fig. 8 is an enlarged cross section on the line 8—8 Fig. 4.

In carrying out the invention I will first describe the same as applied to a horizontal long stroke engine being the structure shown in Figs. 1, 2 and 3. In these figures A represents the bed plate or frame of the engine, and B the cylinder thereof surrounded by the water-jacket C. D is the usual crank shaft with the crank D' thereon, and D² is the connecting rod pivoted at d to the piston E. d' are the usual packing rings in the piston. E' represents any suitable form of igniter, that shown being an electric spark plug, the connections therefor not being shown as they may be of any well known construction. F is the exhaust pipe con-

trolled by the exhaust valve G, a spring G' surrounding the stem G² of the exhaust valve G, and tending to keep it normally closed. Pivoted to a bracket H which extends from the exhaust pipe F is a lever H' one end adapted to bear on the end of the exhaust valve stem G² while to the other end is pivoted the valve rod H² which extends through the bearing H³ on the frame and is provided with an anti-friction roller H⁴ on its end. On the crank shaft D is a cam D³ adapted at each revolution of the shaft to bear against the roller H⁴ and move the valve rod H² to open the exhaust valve G. It will be observed that this cam D³ is tapered so that by shifting longitudinally on the shaft it may operate to hold the exhaust valve open for a greater or less length of time. This cam is mounted on a sleeve D⁴ splined to the crank shaft by the spline D⁵ and provided with a groove D⁶ in which a yoke D⁷ travels. Thus by shifting this yoke the cam is shifted along the crank shaft. J represents the intake valve shown in detail in Fig. 2, and consisting of the usual form of valve J with a stem J' surrounded by a spring J² which tends to keep it normally closed, thus closing the gas admission pipe J³ and allowing the valve to open when a suction is created in the cylinder by the movement of the piston. Located in the cylinder at a pre-determined point are the gas admission ports K and on the exterior of the cylinder and surrounding these ports is a channel K'. The gas admission pipe J³ discharges into this channel K'. The operation of this form of the structure is as follows: In Fig. 1 the piston is at the ignition point, that is to say the gas has been compressed and the piston ready to start on its power stroke. The explosion of the gas drives the piston to the line of the gas ports K, and this has expanded the burned gas to atmospheric pressure or about three volumes. As the end of the piston passes the ports K, because of the fact that the gas in the cylinder behind the piston has been expanded substantially to atmospheric pressure suction will be created and fresh gas will be drawn past the valve J through the channel K' through the ports K and into the cylinder. The piston then moves down until one volume of fresh gas has been admitted through drawing in the necessary fresh charge and this fresh gas is obviously between the end of the pis-

ton and the burned gas. By this time the piston has reached the end of its stroke and starts back, forcing the fresh gas immediately next to it back with it and this fresh 5 gas forces the burned gas ahead of it. In the meantime the cam D^3 has opened the exhaust valve. As soon as the piston starts on its return stroke the burned gas in advance of the fresh gas will be driven off 10 through the exhaust port until the end of the piston has reached such a point that there is nothing remaining in the cylinder except the fresh gas that has been drawn in as described. The cam then rides off from 15 the end of the valve rod and allows the valve to close and the continued movement of the piston to its maximum stroke compresses the fresh gas in the cylinder ready for another ignition.

20 By reference to Figs. 1 and 3, as previously explained the cam D^3 can be shifted along the crank shaft. This is for the purpose of bringing a wider or narrower portion of the cam D^3 , as desired opposite the valve 25 rod H^2 . The object of this is to control the speed of the engine by opening the exhaust valve when the piston is at a greater or less distance from the end of its suction stroke, thus determining the amount of fresh gas 30 that is drawn into the combustion chamber. To illustrate, if the maximum charge of fresh gas is desired the exhaust valve is not opened until the piston reaches the end of 35 its suction stroke, whereas if a less charge of fresh gas is desired, when the amount of fresh gas desired has been drawn into the combustion chamber the exhaust valve is opened thus destroying the vacuum, and allowing either burned gas that has been dis- 40 charged or fresh air, to follow into the chamber. The exhaust valve being located at a point distant from the point where the fresh gas is admitted this admission of either air or burned gas does not in any way affect 45 the fresh gas.

In Figs. 4 to 8 inclusive I have shown the invention embodied in a structure of different form. The structure shown in these latter figures is of a vertical type instead of 50 a horizontal type as above described. This vertical type is what may be termed a short stroke engine and in it as in the horizontal type D represents the crank shaft, D' the crank, D^2 the connecting rod, H^2 the valve 55 rod, H' the exhaust valve lever pivoted to the bracket H , G the exhaust valve, G' the exhaust valve stem, and G' the spring for keeping the exhaust valve normally closed.

In the vertical type, which I am now de- 60 scribing, M represents the cylinder provided with an extension M' both the main cylinder and extension being provided with radiating flanges m such as are ordinarily used on the cylinders of air cooled motors, the purpose 65 being to allow the heat generated by the ex-

plosions to radiate to the atmosphere. N represents the piston, the connecting rod D^2 being pivoted thereon. The piston is also provided with a hollow extension N' which fits in the extension M' of the cylinder. Suitable ports N^2 are provided in the end of the piston N' at the point where it joins the main piston N . E' represents the ignition apparatus preferably an electric spark plug. Formed on the cylinder M by the 70 walls m' and what may be termed the valve or gas ring M^2 is the fresh gas chamber M^3 . The said ring M^2 is shown in detail in Figs. 5 and 6, and is bolted to the flanges m^2 on the walls m' . The gas is admitted to this 75 chamber M^3 through the port M^4 . At four points (although the number may be increased or decreased if desired) in the gas ring M^2 are gas admission ports m^3 (see Fig. 6) and these admission ports are governed by admission valves O, O' , the valve 80 O' being adjacent to the ignition plug, at a slightly higher level than the others, and for the purposes which I will later explain, its spring is somewhat weaker than the 85 others, so that when the piston acts to suck in the fresh gas this valve will open first and admit the fresh gas to a point close to the ignition plug. The operation of this structure is as follows: We will assume that 90 the piston, as shown in Fig. 4, is at its maximum compression point. The gas is exploded and drives the piston down, the burned gas filling the interior of the piston extension N' and the combustion chamber P . 95 In other words the pressure above the end 100 of the cylinder N and in the extension N' is equalized. The piston is driven down until the burned gas has been expanded as in the horizontal construction to atmospheric 105 pressure. As soon as it reaches this point the piston will commence to form a vacuum in the cylinder and this will cause, first the inlet valve, O' , because of its weaker spring, to open and allow fresh gas to enter, and 110 depending upon the strength of the springs around the other valves they will also be opened and allow fresh gas to enter just as in the operation of the horizontal structure. As soon as the piston reaches its maximum 115 downward stroke the cam D' on the crank shaft opens the exhaust valve, and as the piston starts to return the burned gas ahead of the fresh gas both in the main cylinder M and in the hollow piston N' , will be forced 120 out through the exhaust. The fresh gas which has been drawn in behind the piston N forces the burned gas out through the ports N^2 and out through the hollow piston N' to the exhaust.

In practice the valve G will probably be closed a little more than one volume from the end of the upward stroke so as to insure the retention of all the fresh gas and thus a small quantity of burned gas will re- 130

main around the exhaust valve. This is not essential, however, it only being necessary to close the exhaust valve G at such time as is desired in order to secure the desired compression as the piston completes its upward stroke.

It will thus be seen that I have produced an explosive engine in which the proportions and arrangements of parts and the arrangement of valves is such that as soon as the piston in its movement after the explosion has expanded the charge to atmospheric pressure fresh gas is admitted, in such a way, and to such a point that when the piston starts on its return stroke it discharges the burned gas first and then compresses the fresh gas.

This form of engine has many advantages among which are; that the exhaust gas is always discharged into the atmosphere at atmospheric pressure, thus obviating the necessity of a muffler at the exhaust; that with the use of a given amount of fuel a large increase in power is obtained; that the engine will run much cooler than the ordinary engine for the reason that the maximum efficiency of the fuel is utilized as power; that by it an explosion is obtained at every revolution; and that it is simple in construction, and efficient in operation.

While I have herein used the term "gas", I wish to be understood as contemplating by that word any explosive mixture.

Having now fully described my invention, what I claim as new and desire to secure by Letters Patent is:

1. In an explosive engine the combination with the cylinder, the piston, the ignition means, and the exhaust valve, of a fresh gas admission valve adapted to admit fresh gas before the completion of the stroke of the piston due to the explosion, and means for opening said exhaust valve in advance of the completion of said stroke of the piston whereby the amount of fresh gas admitted is regulated.

2. In an explosive engine the combination with the cylinder, the piston, the ignition means, and the exhaust valve, of a fresh gas admission valve of the suction type adapt-

ed to admit fresh gas before the completion of the stroke of the piston due to the explosion, and adjustable means for opening said exhaust valve in advance of the completion of said stroke of the piston whereby the amount of fresh gas admitted is regulated.

3. In an explosive engine the combination with a cylinder, the piston, and the ignition means of an extension on the cylinder, a hollow extension on the piston, a port or ports through said hollow extension adjacent to the main piston head, one or more fresh gas admission ports governed by valves adjacent to the main cylinder head and an exhaust valve adjacent to the outer end of the cylinder extension.

4. In an explosive engine the combination with the cylinder, the piston and the ignition means of an extension on the cylinder, a hollow extension on the piston adapted to travel in said extension on said cylinder, one or more ports in said hollow extension adjacent to the main piston head, one or more fresh gas admission valves located adjacent to the main cylinder head and an exhaust valve located adjacent to the outer end of the extension cylinder.

5. In an internal combustion engine, a combination with a cylinder and igniting means, of a piston movable within said cylinder and having a stroke sufficient to permit the ignited charge to expand in the cylinder and below atmospheric pressure before the completion of the working stroke, means for admitting a combustible charge into the cylinder along the face of the piston when the piston reaches approximately the point in its working stroke where the pressure in the cylinder becomes approximately that of the atmosphere, and a mechanically-actuated exhaust valve in the end of the cylinder in which the piston lies at the beginning of the working stroke.

In testimony whereof, I sign this specification in the presence of two witnesses.

LEVI S. GARDNER.
